(57) **CLAIM**

The ornamental design for a transportation robot, as shown
and described.

DESCRIPTION

FIG. 1 is a top, front and left side perspective view of a
transportation robot;

FIG. 2 is a bottom, rear and left side perspective view
thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

In the drawings the broken line portions form no part of the
claimed design.

1 Claim, 5 Drawing Sheets
